UNITED STATES PATENT OFFICE

161,026

COMBINATION LIGHT FIXTURE, PLANT HOLDER, AND THE LIKE

William L. Hollander, Centralia, Mo., assignor to
A. B. Chance Company, Centralia, Mo., a corporation of Missouri

Application November 8, 1949, Serial No. 5,926

Term of patent 14 years

(Cl. D48—15)

To all whom it may concern:

Be it known that I, William L. Hollander, a citizen of the United States, residing at Centralia, in the county of Boone and State of Missouri, have invented a new, original, and ornamental Design for Combination Light Fixture, Plant Holder, and the like, of which the following is a specification, reference being had to the accompanying drawing, forming part hereof.

In the drawing:

Fig. 1 is a view in perspective of a combination light fixture, plant holder, and the like, showing my new design, the opposite side being of the same appearance; and

Fig. 2 is a bottom plan view.

Fig. 3 is a transverse sectional view, taken on the plane of the line 3—3 of Fig. 2, looking in the direction of the arrows;

Fig. 4 is a transverse sectional view, taken on the plane of the line 4—4 of Fig. 2, looking in the direction of the arrows;

Fig. 5 is a transverse sectional view, taken on the plane of the line 5—5 of Fig. 3, looking in the direction of the arrows.

I claim:

The ornamental design for a combination light fixture, plant holder, and the like, as shown and described.

WILLIAM L. HOLLANDER.
